(57) **CLAIM**

The ornamental design for the tubular chair, as shown and described.

DESCRIPTION

FIG. 1 is a front prospective view of a tubular chair having a tubular frame showing our new design;

FIG. 2 is a left side view thereof, the right side view being a mirror image thereof;

FIG. 3 is a front view thereof;

FIG. 4 is a rear view thereof;

FIG. 5 is a top view thereof; and,

FIG. 6 is a bottom view thereof.

The fragmented crosshatching shown on the seat and backrests understood to represent fabric and would be continuous throughout the circumscribed areas.
